OR D 3,503

Improvement in
Irene leaves.

No. D 3,503

0770. R. Nitzeck

United States Patent Office.

OTTO R. NITSCH, OF NEW YORK, N. Y.

Design No. 3,503, dated May 18, 1869.

DESIGN FOR A FAN-LEAF.

The Schedule referred to in these Letters Patent and making part of the same.

To all whom it may concern:

Be it known that I, OTTO R. NITSCH, of the city of New York, in the county of New York, and State of New York, have originated and designed a new Pattern for Fan-Leaf, of which the following is a full, clear, and exact description, reference being had to the accompanying drawings, making part of this specification.

The invention consists in puncturing the upper portions of fan-leaves with a series of holes of various forms, arranged as hereinafter set forth.

The broader ends of the leaves are connected by means of a ribbon, which passes through slits or openings in the same.

Immediately below the ribbon each leaf is punctured with a series of small round holes, arranged to form a figure, which, while sector-shaped, has the appearance of being a rectangle.

Enclosed within this figure are two rows of larger holes, the outer rows of each row being rectangular, and the two central ones Δ , or cone-shaped.

The perforation in the central space, between the two latter, is diamond-shaped.

Above the ribbon, each of the leaves is also punctured, to form a figure having a straight base, its three other sides corresponding in form to the outline or shape of the upper end of the leaf.

A larger oblong opening is, however, made in place of a round one in the centre of the curved portion of said figure.

Two similar openings are made immediately below, and below these still two others of the same shape, but having their larger axes at right angles the same and parallel to the upper or "keystone" opening.

Between the two last named are two rectangular holes, and between these another, which is diamond-shaped.

Below the latter is another opening of a similar form, on each side of which is another, which is triangular in shape.

In the lower portion of the figure is a row of three triangular openings, and next above two, which are heart-shaped.

The larger and smaller perforations are intended to be arranged equidistant respectively each from the other.

Claim.

What I claim as my invention, and desire to secure by Letters Patent, is—

The design for a fan-leaf, herein described and shown.

O. R. NITSCH.
